STENCIL DUPLICATING MACHINES

Thomas G. Howe, Tottenham, England, assignor to Gestetner Limited, London, England, a corporation of Great Britain

Application December 14, 1953, Serial No. 398,164

6 Claims. (Cl. 101—118)

In stencil duplicating machines, such as for office use, there is provided a pressure roller movable towards and away from the cylinder of the machine in synchronism with the paper feed whereby when a sheet is advanced for duplicating the roller is raised to press the sheet against the stencil which is wrapped round the cylinder. The pressure roller is actuated from the driving motor or handle, being raised and lowered as each sheet is fed through the machine. The pressure roller is actuated by a clutch mechanism controlled by a paper detector so that if a sheet of paper is not fed forward the roller is not raised—as otherwise the roller would engage the stencil and be coated with ink which is clearly undesirable. With increase in the speed of operation of the machine there is a tendency, beyond a certain speed of operation, for the paper detector and the clutch mechanism (which is cam operated) not to be accurately controlled by the cam and consequently for vibration to be set up in the machine. Additionally there is the possibility that the detector may permit the roller to engage with the stencil and become coated with ink.

The present invention aims to provide an improved mechanism for controlling the pressure roller by the paper detector.

Another object of the invention is to ensure that the cam movements are accurately applied to the pressure roller and to the paper detector at higher speeds than those at present prevailing.

The paper detector usually comprises a finger or fingers lowered by spring means to engage the top of each sheet of paper after the latter has been fed forward and the cam follower has been provided to actuate the paper detector and a clutch throw-out mechanism, said spring means being effective also to hold the cam follower against the cam. A further object of this invention is the provision of separate spring means for the paper detector and for the cam follower.

Another object of the invention is to provide that the paper detector be controlled separately of the cam follower so that a light and sensitive detection of the presence of paper is possible while ensuring that the cam follower is effectively held against the cam at all speeds of operation. This and other objects of the invention will be better understood from the following description of a duplicating machine in accordance with the present invention. The description which follows is made with reference to the accompanying drawings of which:

Figure 1 is a side view of a stencil duplicating machine illustrating the paper detector and the pressure roller actuating mechanism, the mechanism being shown in the position assumed in the absence of a sheet of paper.

Figure 2 is a view corresponding to Figure 1 and showing certain parts of the mechanism during detection of the presence of a sheet of paper.

Figure 3 is an end view showing certain details of the mechanism of Figures 1 and 2, and

2

Figure 4 is a view of a mechanism for raising and lowering a pressure roller.

Referring to Figure 1: the duplicating machine comprises side frames 5 between which are rotatably mounted an upper cylinder 6 and a lower cylinder 7 around which passes a silk screen 8 to which a stencil may be attached in well known manner. The cylinders 6 and 7 are rotated by the handle 9 (part only of which is shown) which drives gear wheel 10 meshing with a pinion 11 carried on the spindle of cylinder 7. The pressure roller 12 is supported from a shaft 13 carried by brackets (not shown) secured to the frames 5. The shaft 13 is secured to a lever 14 which constitutes part of a mechanism for raising the roller 12 to engage a sheet of paper being fed through the machine, the lever 14 being operated, through a pair of cam followers 15, 15', by a cam 16. If reference be made of Figure 4, it will be noted that the cam followers 15, 15' are adapted to engage opposite sides of the cam 16 and are secured to a carrier plate 70 which is slidably mounted in guide ways 71 projecting from a member 72. The plate 70 is formed with an arcuate slot 73 which receives a pin 74 carried by a lever 75. The lever 75 is pivotally supported at 76 and is integral with a second lever 77. The lever 77 carries a block 78 coupled to the lever 14 by way of a connecting rod 79. Rotation of the cam 16 will therefore slide the carrier plate 70 to and fro along the guide ways 71, movement of the plate 70 being transmitted by the levers 75, 77 to the shaft 13 and hence to the pressure roller 12 so as to raise and lower it. The shape of the cam 16 and the spacing of the followers 15, 15' is such that when the cam is moved through angular positions such that the pressure roller 12 is being raised or is being maintained in contact with the cylinder 7, the followers 15, 15' closely engage opposite sides of the cam 16. This is illustrated in Figure 4, where the cam 16 is shown in the position corresponding to the position of maximum lift of the pressure roller. It will be appreciated that this construction, which is more fully described in the specification of my copending application Serial No. 398,162, ensures that when the cam 16 is in the position shown in Figure 4 it accurately and positively controls the position of the plate 70 since its opposite sides are engaged by the followers 15, 15' at this time. Rebound of the pressure roller on hitting the cylinder 7 is therefore prevented.

The cam 16 is driven from a gear wheel 17 which meshes with a pinion 18 driven by gear 11. Within the gear wheel 17 there is disposed a clutch (Figure 2) comprising an arm 19 pivoted at 20 and having a claw 21 to enter a notch 22 in the gear wheel 17. The arm 19 is carried on a shaft to which the cam 16 is attached. A pin 23 projects sideways from the arm 19 as more fully shown in Figure 3. A spring 24 urges the claw 21 into the notch 22. When the claw 21 lies within the notch 22 gear wheel 17 is drivingly connected to the cam 16 and the pressure roller is raised as more fully described in the specification of copending application Serial No. 398,162. As indicated by the arrows in Figures 1 and 2 the clutch assembly rotates anti-clockwise so that if the pin 23 is brought against an obstruction the arm 19 is rocked to disengage the claw 21 from the notch 22 with the consequence that the drive to the cam 16 is interrupted. Consequently the pressure roller 12 will not be raised.

Projecting into the line of path of the pin 23 is a finger 25 of a slider 26 which is carried by the frame of the machine. The slider 26 has a cut out 27 to receive a finger 28 forming part of a lever 29 pivoted at 30 and carrying a paper detector finger 31 which co-operates with a plate 32 having holes 34 to receive the fingers 31.

When a sheet of paper is fed forward it travels across the top of the plate 32—such a sheet of paper is indicated at 33 in Figure 2. A spring 35 urges fingers 31 against the plate 32 and to bring the finger 28 against the face 36 of slider 26. The lever 29 carries a pin 37 which is urged by spring 35 against arm 38 of a lever 39 pivoted to the frame at 40 and carrying a cam follower 41 to engage the cam 42 which is driven by means (not shown) from the handle 9. A spring 43 maintains the follower 41 against the cam 42.

With the arrangement so far described the cam 42 acts to swing arm 38 so that spring 35 rocks lever 29 with the finger 28 moving within cut out 27. At the same time the fingers 31 of the paper detector are moved towards plate 32. While a sheet of paper 33 rests on the plate 32 the fingers 31 will engage with the top of the sheet of paper and further movement of the lever 29 (which is permitted by the arm 38) is prevented and the finger 28 stops short of the face 36. However, if there is no paper the fingers 31 pass through the holes 34 (see Figure 1) and finger 28 is brought against face 36 to move the slider 26 so that the finger 25 thereof is brought into the path of pin 23 with the result that the clutch is disengaged as described above and the pressure roller 12 is not raised.

A latch 45 is carried at 46 by the slider 26 and is urged by spring 47 to engage behind a notch 48 (see Figure 1) of slider 26 when the latter is advanced to disengage the clutch. When arm 38 is next moved clockwise it engages pin 37 to move lever 29 anti-clockwise. However, slider 26 is held against movement by the latch 45 until arm 49 of lever 29 engages pin 50 of latch 45 to raise the latter and to move the slider 26 whereby finger 25 is withdrawn from the pin 23. It will be apparent therefore that when the slider 26 is advanced to disengage the clutch it is held in this position until another sheet of paper is about to be fed forward.

It is a particular advantage of the present invention that the spring 35 is independent of the spring 43 since it is permitted thereby that the spring 43 be readily chosen to ensure that the cam follower 41 is held in engagement with the cam 42, while the spring 45 may be relatively light such as will ensure that the fingers 31 effectively detect the presence of a sheet of paper on the plate 32 without, however, puncturing the paper and passing into the holes 34. By the provision of independent springs for the paper detector and for the cam follower the spring 43 may be selected to ensure that at all speeds of operation the cam follower will be maintained against the cam.

When the machine is inoperative in the sense that duplication has ceased although the cylinders 6, 7 may continue to be driven e. g. a specified number of copies has been run off or for other reasons the paper feed mechanism is automatically rendered inoperative. At other times the paper feed mechanism is rendered inoperative by manual means, for instance by a finger piece 55 which for this purpose is set to the position shown in Figure 1. At all times when the paper feed is inoperative it is essential that the clutch comprising parts 21, 22 is prevented from engagement to ensure that the pressure roller cannot be raised. Accordingly it is arranged that the finger piece 55 (or other mechanism actuated when a specified number of copies has been run off) adjusts an arm 56 carrying a pin 57 which en-

gages the inclined face 58 of a lever 59 pivoted at 60 and having a claw 61 which embraces a pin 62 carried by the slide 26. The spring 47 is anchored to the lever 59 tending to urge the pin 62 towards the right. When the arm 56 is thus brought to the position shown in Figure 1 such movement by spring 47 is permitted with the consequence that the finger 25 of the slide 26 is advanced to lie in the path of the pin 23 and thereby prevent the clutch from being engaged while the paper feed is stopped.

10 I claim:

1. A stencil duplicating machine comprising a frame, a cylinder rotatably mounted in the frame and carrying the stencil, a pressure roller, a support for the pressure roller whereby the roller is movable towards the cylinder to press a sheet of paper against the stencil, means for advancing the pressure roller to engage a sheet of paper fed into the machine to press it against the stencil, said means for advancing the pressure roller being driven from said cylinder driving means, a clutch to interrupt the drive to the means for advancing said pressure roller, means for disengaging said clutch, means to detect each sheet of paper as it is fed forward for duplicating and for actuating said clutch-disengaging means on the absence of paper, spring means urging the detector means into engagement with the paper sheet, a cam-follower means for actuating said clutch-disengaging means and to retract the paper detector from the paper, spring means to maintain the follower in engagement with the cam and a common means for driving the cylinder, said cam and the means for advancing the pressure roller.

2. A stencil duplicating machine as claimed in claim 1 wherein the paper detector comprises a spring-urged lever carrying a finger to engage the upper surface of the sheet of paper whereupon movement of the lever by said spring means is prevented and there is a slide which actuates the clutch to disconnect the drive to the pressure roller, absence of paper permitting further movement of the lever whereby a finger of the lever engages said slide to disconnect the drive to the pressure roller.

3. A stencil duplicating machine as claimed in claim 2 in which there is a latch to hold the slide in an advanced position corresponding with the drive to the clutch being disconnected.

4. A stencil duplicating machine as claimed in claim 2 comprising a lever arm against which said lever of the paper detector is held by said spring means, said lever arm being actuated by said cam mechanism to control movement of the spring-urged lever of the paper detector.

5. A stencil duplicating machine according to claim 3 wherein movement of said spring-urged lever in the direction opposite to that which results in detection of the paper operates means to release said latch to permit return of the slide.

6. A stencil duplicating machine as claimed in claim 5 in which a spring is connected to urge the latch to its slide-engaging position and manual selecting means is provided to cause said spring to advance the slide to disengage the clutch.
